UNITED STATES PATENT OFFICE.

WILLIAM G. FISHER, OF SUNBURY, PENNSYLVANIA.

SHUTTLE GUARD FOR LOOMS.

1,406,835.

Specification of Letters Patent. Patented Feb. 14, 1922.

Application filed September 26, 1921. Serial No. 503,413.

To all whom it may concern:

Be it known that I, WILLIAM G. FISHER, a citizen of the United States, residing at Sunbury, in the county of Northumberland 5 and State of Pennsylvania, have invented certain new and useful Improvements in Shuttle Guards for Looms, of which the following is a specification.

This invention relates to looms of the ordinary type and has for its object the improvement in shuttle traps or guards for the same, being adapted in the event of a shuttle flying out of the warp to confine the shuttle in the trap or guard and thus safe 15 guard the operator or bystander.

The various features of the invention will be hereinafter more fully described in connection with the accompanying drawing, in which:—

20 Figure 1 is a front elevation of a hand rail and lay beam of a loom with the shuttle guard attached to the former.

Figure 2 is a section taken at right angles to Figure 1 and in a plane indicated by line 25 2—2 of said figure showing the guard in a raised and normal position.

Figure 3 is a sectional view of hand rail and trap with inwardly opening shutters.

Figure 4 is a top plan view of the shutters 30 as attached to the trap.

Figure 5 is a sectional view of the shutters, holder, and spring.

Referring to the drawing, 1 indicates the hand rail and 2 the lay beam of an ordinary 35 loom. Permanently secured to the top of the hand rail 1 is a metal strip 3. 4 indicates a metallic strip covering the front face of the hand rail 1, being hinged to the strip 3 at 5.

Secured to the strip 4 in any suitable 40 way are a plurality of inverted U-shaped holders 6 on the inner face of which are secured a plurality of spaced parallel rods 7 forming a cage. The rods 7 at the ends of the cage converge and are held in 45 place by solid inverted U-shaped holders 8 closing the ends of the cage.

In the lowermost rods of the cage are incompletely grooves in which operate and fit straps 9, one end of which abuts against 50 the shoulders 10 and the other ends are suit-

ably secured to shutters 11. Springs 12 surround the lowermost rods of the cage and engage the tops of the shutters 11, the purpose of which is to hold the shutters in their closed positions, the shutters opening inward. The guard as herein described may be applied to any form of loom in which a shuttle is used.

In practice it will be observed that in the event of the shuttle flying out of the warp (shown by dotted lines in Figure 1) it will strike the bottom of the shutters 11 at an angle as shown by dotted lines, pass through the said shutters, the upper end striking the top of the cage or guard and deflected into a horizontal position inside the cage on top of the shutters. The guard can then be raised to the position shown in Figure 2, the shutters opened inward and the shuttle removed. From this it follows that the shuttle is effectually prevented from forcibly leaving the loom and injuring an operator or bystander as frequently happens when no means is provided for retaining the shuttle in the loom.

What I claim as new and desire to secure by Letters Patent, is:—

1. A shuttle trap for looms comprising a semi tubular structure having closed ends and arranged over the lay beam, said structure having in its lower side a plurality of shutters adapted to open inwardly.

2. A shuttle trap for looms comprising a semi tubular structure having closed ends and arranged over the lay beam, said structure having in its lower side a plurality of relatively short shutters adapted to open inwardly.

3. A shuttle trap for looms comprising a semi tubular structure having closed ends and arranged over the lay beam, said structure having in its lower side a plurality of two opposed series shutters adapted to open inwardly.

4. A shuttle trap for looms comprising a semi tubular structure having closed ends and arranged over the lay beam, said structure having in its lower side a plurality of shutters adapted to open inwardly, means for holding said shutters in place.

5. A shuttle trap for looms comprising an elongated structure of semi tubular form in cross section composed of connected parallel rods, the ends of said structure being closed, 5 said structure having in its lower side a plurality of shutters adapted to open inwardly held in normal position by means of springs.

In testimony whereof I affix my signature in presence of two witnesses.

WILLIAM G. FISHER.
